UNITED STATES PATENT OFFICE.

GUYTON D. SAVAGE, OF NORFOLK, VIRGINIA.

DESIGN FOR A RING.

Application filed January 22, 1927. Serial No. 20,455. Term of patent 3½ years.

To all whom it may concern:

Be it known that I, GUYTON D. SAVAGE, a citizen of the United States of America, and a resident of Norfolk, in the county of Norfolk and State of Virginia, have invented a new, original, and ornamental Design for a Ring, of which the following is a specification, reference being made to the accompanying drawing, forming a part thereof.

Fig. 1 is an edge view of the ring showing my new design.

Fig. 2 is a side view of the ring shown in Fig. 1.

I claim:

The ornamental design for a ring, as shown.

GUYTON D. SAVAGE.
